(57) **CLAIM**

The ornamental design for an edible shoe-shaped dental chew for animals as shown and described.

DESCRIPTION

4. Edible shoe-shaped dental chew for animals

Figure 4.1 is a front, top and right side perspective view of an edible shoe-shaped dental chew for animals, showing my new design;

Figure 4.2 is a front elevation view thereof;

Figure 4.3 is a bottom plan view thereof;

Figure 4.4 is a back elevation view thereof;

Figure 4.5 is a left side elevation view thereof;

Figure 4.6 is a top plan view thereof;

Figure 4.7 is a right side elevation view thereof;

Figure 4.8 is a back, top and left side perspective view thereof; and

Figure 4.9 is a bottom and right side perspective view thereof.

The broken lines shown in Figures 4.1–4.9 illustrate portions of the edible shoe-shaped dental chew for animals, that form no part of the claimed design.
